Inventor

UNITED STATES PATENT OFFICE.

FREDERICK A. TYLER, OF ROME, NEW YORK.

FILE-CABINET.

SPECIFICATION forming part of Letters Patent No. 451,535, dated May 5, 1891.

Application filed September 30, 1890. Serial No. 366,655. (No model.)

To all whom it may concern:

Be it known that I, FREDERICK A. TYLER, a citizen of the United States, residing at Rome, in the county of Oneida and State of New York, have invented a new and useful 5 File-Cabinet, of which the following is a specification.

My invention relates to that class of cabinets which are adapted for the reception of 10 file-cases, said cases when drawn out being supported in convenient position for the removal of the papers that may be within the cases; and my invention consists in certain features of novelty to be hereinafter described, 15 and then pointed out in the claim.

In the accompanying drawings, Figure 1 is a perspective view showing a complete cabinet with some of the file-cases drawn out. Fig. 2 is a vertical longitudinal section through 20 one of the cells and its case when drawn out, showing the preferred form. Fig. 3 is a horizontal section thereof. Fig. 4 is a horizontal section showing a modification. Fig. 5 is a horizontal section of another modification.

25 The cabinet 1 is provided with any suitable number of shelves 2, divided by vertical partitions 3, forming cells 4. At the sides of the cabinet two-part folding doors (not shown) may be provided, if desired, to protect the 30 boxes or drawers 6 in the cabinet from dust. At each side of the bottom of the case I provide a series of shelves 7, for the reception of legal blanks, &c., the spaces occupied by the shelves being closed by small doors 8. Between 35 the two series of shelves 7 is a drawer 9, for the reception of miscellaneous articles.

In the preferred form of my invention, shown in Figs. 2 and 3, 10 represents a strip 40 projecting from the rear edge of the bottom of one of the cells toward the front, said strip receiving a slide 11, which telescopes thereon, and said slide being pivotally connected at 12 midway of the boxes. Within the boxes I provide followers 13, composed of bail-shaped pieces of wire, the lower ends of which 45 are formed into coil-springs 14, secured to the sides of the boxes. The follower 13 serves to retain the papers within the box. When the boxes are pulled out about half-way, they will 50 tip over into vertical position in front of the cabinet, thus being within easy access.

In the modified form shown in Fig. 4, 15 represents sliding strips pivoted at 16 to each side of a box 6, and provided at their inner ends with inturned portions or stops 17. 55 These sliding strips are received by guides 18 at each side of the cells and near the bottom thereof.

In the modified form shown in Fig. 5, 19 is a slotted plate or slide, to which the boxes 60 are pivoted at 20. In the bottom of each cell is a headed stud or pin 21, which is received by the slot 22 of the slide 19, thus guiding the latter in its movements.

In all the forms shown it will be observed 65 that the boxes are pivotally connected with slides that are guided within the cells, said slides being adapted to support the boxes in position when drawn out, as shown in Fig. 1.

The filing boxes or cases may be made 70 square, or of any other desired form, and of iron, wood, paper, or any other suitable material. The boxes are provided with pulls 24.

In connection with my file-cabinet I prefer 75 to employ the hereinafter-described system of indexing - cases filed away of lawyers. This consists in providing an index-book in which is entered, for instance, say a case of Jones vs. Smith, under J; Jones vs. Smith, file 10; S. Smith adverse Jones, file 10; giving 80 a double indexing of a single case or pleading. The boxes are preferably numbered in series, as shown in Fig. 1. For merchants, county clerks, offices, or private use, the boxes may be alphabetically or re-alphabetically arranged, or with suitable labeling, such as 85 bills payable or receivable, statements, letters, receipts, contracts, or any other method of designating the contents.

What I claim is—

The combination, with the file-box, of a 90 slide pivoted thereto, a support for said box, and a strip projecting forwardly, said slide telescoping onto said strip, substantially as set forth.

95 In testimony that I claim the foregoing as my own I have hereto affixed my signature in presence of two witnesses.

FREDERICK A. TYLER.

Witnesses:

J. S. TYLER,
C. W. PARMELEE.
